CLAIM

I claim the ornamental design for an assisting instrument for sleep, as shown and described.

DESCRIPTION

FIG. 1 is a front view of an assisting instrument for sleep;
FIG. 2 is a rear view thereof;
FIG. 3 is a left-side view thereof;
FIG. 4 is a right-side view thereof;
FIG. 5 is a top view thereof;
FIG. 6 is a bottom view thereof;
FIG. 7 is a front perspective view thereof; and,
FIG. 8 is a rear perspective view thereof.
The broken lines depict portions of the assisting instrument for sleep in which the design is embodied that form no part of the claimed design.
